WARE.

MECHANICAL SIGNAL.

1,172,743.

Specification of Letters Patent. Patented Feb. 22, 1916.

Application filed February 14, 1912, Serial No. 677,458. Renewed July 8, 1914. Serial No. 649,833.

To all whom it may concern:

Be it known that I, CHARLES F. SENDALL, a citizen of the United States, residing at Brooklyn, in the county of Kings and State 5 of New York, have invented new and useful Improvements in Mechanical Signals, of which the following is a specification.

This invention relates to signal horns and especially those operated by mechanical 10 means and where a diaphragm is vibrated by means of a rotating wheel operated by the necessary mechanism, the signal horn being so constructed and the diaphragm arranged so that the mechanism may be housed 15 within the projector to protect it and at the same time economize in space as will be more fully described in the following specification, set forth in the claims and illustrated in the drawings, wherein,

20 Figure 1 is a longitudinal vertical sectional view of the signal horn comprising this invention. Fig. 2 is a horizontal sectional view of same.

The projector 5 is preferably rectangular 25 in cross section and has a flared front end 6 to prevent too sudden liberation of the sound waves, as is common in this type of signaling apparatus. Within the projector is a frame 7, slidable lengthwise of the projector, 30 and normally rigidly held against movement. The frame rests upon the one side of the projector, and has arms 7^a engaging with the opposite side. The endwise movement is secured by means of an adjustment 35 screw 8 at the front end of the frame and extending through a standard or lug 9 rigid with the projector. Nuts 10, threaded on the screw engage with opposite sides of the lug to hold the parts rigid in respect to each 40 other. The rear end of the projector is flared and provided with a flange 13 within which fits the diaphragm 12, so as to close the rear end of the projector. The dia- 45 phragm carries a suitable wearpiece 11 on its front face against which the cam of the operating mechanism engages, as will be more fully pointed out hereinafter. By loosening one of the nuts of the screw 8, and 50 tightening the other, the frame which carries the cam may be adjusted toward or from the diaphragm, so as to secure the desired overlap of cam on wearpiece. In the rear of the diaphragm, I provide a rear wall 15 spaced from the diaphragm preferably by 55 an annular gasket 14, so that an air chamber

is left in the rear of the diaphragm, between the latter and said rear wall.

The frame 7 has three uprights, 16, 17 and 18 which form bearings for and carry shafts 19, 20, and 21. The shaft 19 carries a toothed wheel 22 of any desired pattern and which makes contact with the button or wearpiece 11 so that upon the rotation of the wheel the teeth or cams will repeatedly strike the button and force the diaphragm 60 backward, releasing it when the spaces between the teeth allow the button to move forward again. The shaft 19 also carries a pinion 23, driven by a gear wheel 24 on the shaft 20 and the latter is rotated by means 65 of the pinion 25, driven by the gear wheel 26 on the shaft 21. This shaft 21 carries a handle in the form of a yoke 27 which may be operated by any desired means such as the pressure of the hand or it may be connected 70 by means of a cord or link with a lever near the driver's seat. A pawl 30 is carried by an arm 28 and engages with a ratchet wheel 31 on the shaft 21. The arm 28 is rigid with the shaft 21 and has attached to it a spring 75 29 adapted to normally hold the shaft, arm, and handle in one predetermined position. When the handle is driven in the direction of the arrow in Fig. 1, it rotates the train of wheels, multiplying the speed so that the 80 ratchet wheel 22 is rotated with such rapidity that the ear can hardly distinguish the separate vibrations of the diaphragm and a continuous tone may result as long as the yoke continues to move. The signal 85 horn as thus constructed, is adapted to protect its mechanism and store same within the projector and at a point where it will not be interfered with by the other parts of the automobile while the mechanism occupies 90 so little of the space within the projector horn that the noise is in no way retarded or lessened nor its operation on the resonator interfered with. By adjusting the screw 8, 95 the vibration of the diaphragm may be regulated so as to subdue or increase the vibrations and noise.

It is obvious that the parts may be otherwise arranged or modified while carried within the projector horn without departing from the essential features above described.

What I claim as new and desire to secure by Letters Patent is,—

1. In a signal, the combination with a 110

projector of a diaphragm and wearpiece at the rear end of the projector, of a frame carried within the projector, an adjusting screw at the front end of the frame and carried by the projector, a ratchet wheel journaled at the rear end of the frame and adapted to make contact with the wearpiece, a pinion on the shaft with the ratchet wheel, a gear wheel meshing with the pinion and having a second pinion on its shaft, a shaft with a gear wheel meshing with the second pinion, a yoke on the outer ends of the latter shaft, an arm with a pawl on the shaft, a ratchet wheel connected with the latter gear wheel, and a spring adapted to return the arm with the pawl and the yoke to their normal positions.

2. In a signal, the combination with a projector, of a diaphragm and wearpiece at the rear end of the projector, of a frame carried within the projector, an adjusting device at the front end of the frame, a toothed wheel journaled at the rear end of the frame and adapted to make contact with the wearpiece, a pinion on the shaft with the toothed wheel, an intermediate shaft carrying a gear wheel meshing with the pinion, a shaft carrying a lever arm, an arm with a pawl on the shaft, a toothed wheel loosely mounted on the latter shaft, gearing connecting the last named toothed wheel and intermediate shaft, and a spring adapted to return the arm with the pawl and the lever arm to their normal positions.

3. A warning signal for vehicles, having a diaphragm and a projector extending forward therefrom, in combination with a solidly supported rotary mechanical agitator in front of the diaphragm, an operating handle, and a multiplying gearing contained in the projector to impart speeded rotation to the agitator.

4. A warning signal for vehicles, having a diaphragm and a projector extending forward therefrom, in combination with a frame in the projector having means for adjustment with relation to the diaphragm, a rotary mechanical agitator and a multiplying gearing with one-way driving means mounted on said frame, and an oscillatory handle outside of the projector and in front of the diaphragm adapted by a partial revolution in one direction to impart speeded rotation to said actuator through said gearing and having means for returning it in the opposite direction.

5. A warning signal for vehicles, having a diaphragm and a projector extending forward therefrom, in combination with a solidly supported rotary mechanical agitator in front of the diaphragm, an operating lever arm, and a multiplying gearing contained in the projector to impart speeded rotation to the agitator.

6. A warning signal for vehicles, having

a diaphragm and a projector extending forward therefrom, in combination with a frame in the projector, a rotary mechanical agitator and a multiplying gearing with one-way driving means mounted on said frame, and an oscillatory lever arm adapted by a partial revolution in one direction to impart speeded rotation to said actuator through said gearing and having means for returning it in the opposite direction.

7. A horn or signaling device, comprising a diaphragm presenting a wear-piece a tubular casing secured to said diaphragm about the periphery thereof, a train of gears in said casing, shafts substantially parallel to said diaphragm and carrying said gears, a cam rigid with one terminal gear of said train and adapted to engage with said wear-piece, a ratchet wheel rigid with the other terminal gear of said train and loose on its supporting shaft, a spring pressed dog carried by said shaft for engagement with said ratchet wheel, said last mentioned shaft having its terminal portions projecting out through opposite sides of said casing and a U-shaped bail outside of said casing and having its opposite ends secured to said last mentioned shaft, the center portion of said bail being movable toward and from the plane of the diaphragm to effect a rotation of said cam and a vibration of said diaphragm.

8. A horn or signaling device comprising a diaphragm, a resonator, a cam rotatable about an axis substantially parallel to said diaphragm, a shaft substantially parallel to said diaphragm and having a ratchet wheel rotatably mounted thereon, a dog carried by said shaft for engagement with said ratchet wheel, a train of gears from said ratchet wheel to said cam and a U-shaped bail having its opposite ends secured to opposite ends of said shaft whereby said cam may be rotated to vibrate said diaphragm upon a swinging of the center portion of said bail in one direction.

9. A horn or signaling device comprising a tubular casing, a diaphragm closing one end thereof, a cam within said casing and rotatable about an axis substantially parallel to said diaphragm, a shaft substantially parallel to said diaphragm and having a ratchet wheel loosely mounted thereon, means carried by said shaft for engagement with said ratchet wheel to rotate the latter upon an oscillation of said shaft in one direction, a train of gears from said ratchet wheel to said cam and a bail having its opposite ends secured to opposite ends of said shaft whereby said cam may be rotated to vibrate said diaphragm upon the swinging of the center portion of said bail in one direction, and means for bodily adjusting said cam toward and from said diaphragm.

10. A horn or signaling device, compris-

- ing a diaphragm, a casing secured to said diaphragm about the periphery thereof, a train of gears, shafts supporting said gears, a cam driven by one terminal gear of said train and adapted to vibrate said diaphragm, pawl and ratchet members carried by one of said shafts, one of said members being connected to the other terminal gear of said train and the other member being secured to said shaft, said shaft having a terminal portion projecting out through the side of said casing, and a handle outside of said casing and secured to said shaft and having a portion movable toward and from the plane of the diaphragm to effect a rotation of said cam and a vibration of said diaphragm.
11. A horn or signaling device, comprising a diaphragm presenting a wear-piece, a tubular casing secured to said diaphragm about the periphery thereof, a train of gears
- in said casing, shafts substantially parallel to said diaphragm and carrying said gears, a cam rigid with one terminal gear of said train and adapted to engage with said wear-piece, a ratchet wheel rigid with the other terminal gear of said train and loose on its supporting shaft, a spring pressed dog carried by said shaft for engagement with said ratchet wheel, said last mentioned shaft having a terminal portion projecting out through the side of said casing, and a handle secured to said terminal portion for driving said train of gears and rotating said cam.
